(57) **CLAIM**

The ornamental design for a solar sun rescue reflector charger kit, as shown.

DESCRIPTION

The claimed solar sun rescue reflector charger kit is designed with LED in center of mirror which hooks to battery box for power.

FIG. 1 is a perspective view of a mirror, with light emitting diode in the center.

FIG. 2 is a perspective view of a battery box.

FIG. 3 is a perspective view of a carrying case for FIGS. 1, 2, 4 and 5.

FIG. 4 is a perspective view of a solar panel; and,

FIG. 5 is a perspective view of a battery box with cover.

FIGS. 1 through 5 depict elements of a solar sun rescue reflector charger kit, and are illustrated separately for convenient purposes only.
